UNITED STATES PATENT OFFICE.

THOMAS J. CRAWFORD AND KIRBY J. ATKINSON, OF OMAHA, NEBRASKA.

DESIGN FOR A MOPPING-CABINET.

42,835.

Specification for Design.

Patented July 30, 1912.

Application filed April 26, 1912. Serial No. 693,458. Term of patent 14 years.

To all whom it may concern:

Be it known that we, THOMAS J. CRAWFORD and KIRBY J. ATKINSON, citizens of the United States, residing at Omaha, in the county of Douglas and State of Nebraska, have invented a new, original, and ornamental Design for a Mopping-Cabinet, of which the following is a specification, reference being had to the accompanying drawing, forming a part thereof.

Figure 1 is an end view of a mopping-cabinet showing our new design. Fig. 2 is a

plan view of the same. Fig. 3 is a side view of the mopping-cabinet.

We claim:

The ornamental design for a mopping-cabinet, as shown.

In testimony whereof we have affixed our signatures in presence of two witnesses.

THOMAS J. CRAWFORD.
KIRBY J. ATKINSON.

Witnesses:

HIRAM A. STURGES,
A. F. CLARK.
